HAND-HELD KEYBOARD-OPERATED STRINGED MUSICAL INSTRUMENT

Leonard W. Pavia, 460 Columbia Turnpike,
Florham Park, N.J. 07932

Filed Feb. 26, 1969, Ser. No. 15,932

Term of patent 14 years

Int. Cl. D17—03

U.S. Cl. D56—1

FIG. 1

FIG. 2

FIG. 3

FIG. 1 is a perspective view of a hand-held keyboard-operated stringed musical instrument, showing my design;

FIG. 2 is a top plan view; and

FIG. 3 is a side elevational view thereof.

Portions of the drawing figures are shaded to indicate contrast in appearance.

I claim:

The ornamental design for a hand-held keyboard-operated stringed musical instrument, substantially as shown and described.
